BROODER

Stephen M. Crider, Criders, Va.

Application September 15, 1942, Serial No. 458,414

3 Claims. (Cl. 236—6)

This invention relates to poultry brooders, and is particularly but not necessarily concerned with brooders of the type utilizing wood burning heaters.

Brooders of this type should be capable of low cost production and sale, while at the same time it is desirable that they have the advantages of the more expensive types; and an object of the present invention is to provide a brooder which will meet these requirements.

Another and more specific object of the invention is to provide a brooder heater having a simple compact type of automatic control unit which may be easily and quickly installed and removed in its entirety.

A further object of the invention is to provide a brooder having a heater of the wood burning type which is easy to fire and keep supplied with fuel and which is under automatic control.

The foregoing and other objects and advantages will become apparent in view of the following description taken in conjunction with the drawing, wherein:

Fig. 1 is a transverse vertical section of a brooder embodying the invention;

Fig. 2 is a front elevation of the brooder with the front section of the hood or hover raised to show the front of the heater;

Fig. 3 is an enlarged detail of the control unit;

Fig. 4 is a section taken on the line 4—4 of Fig. 3.

Fig. 5 is a fragmentary sectional view of the upper portion of the brooder.

Referring to the drawing in detail, the brooder is heated by a wood burning stove generally indicated at 10, the stove preferably being of cylindrical or drum shape and made of sheet metal with front and rear end plates 11 and 12 secured to the opposite ends of the drum. The drum is also provided with legs 13 and a stack or chimney 14.

Mounted in the front end of the stove is a door 15 which is provided with hinge pins 16 detachably engaged in hinge lugs 16'. The door may be made of metal of suitable thickness and in actual practice it consists of a casting and carries a closure latch 17. The door is formed with a draft opening 18 which on the outer side of the door is surrounded by an outwardly extending wall 19 having an upwardly inclined or beveled contour, and mounted on this wall is a damper door 20 which is hinged at its upper end to said wall.

The inner side of the door is provided with a shield 18' overlying the draft opening 18 with its

lower end open at 18a and serving to direct the air downwardly into the stove from said draft opening.

Connected to the front of the door is an arm or bracket 21 which projects outwardly and at its outer end is looped or turned inwardly, terminating in a reversely bent free end portion 21'. Mounted on the arm 21 is a lever guiding and supporting member 22 which projects downwardly and serves to support and guide a lever 23, the latter being pivoted to said member 22 by means of pin 24. The one end of the lever 23 has connected thereto a link 25 which detachably engages a hook 26 connected to the damper 20; while the opposite end of the lever 23 is provided with a weight 27. The lever 23 may be in the form of a sheet metal section bent in channel shape and the member 22 forms a restricted longitudinally-extending opening in which the lever has rocking movement.

The free end 21' of the arm 21 is bored and threaded to receive a screw 28 having a thermostat supporting member on its upper end. On this member one or more thermostatic wafers or discs 30 are disposed, said wafers preferably being charged with a suitable expansible fluid affected by temperature changes within a range commensurate with the proper care and comfort of the chicks. The lever 23 is provided with a downwardly projecting portion 31 adapted to contact with central portion of the disc 30.

The upper end of the arm 21 is formed with a toe 21a which is detachably engaged in a lug 32 on the outer face of the door. When the end or toe of the arm is inserted in this lug and the arm released, it will hang in proper operating position together with the entire control assembly carried thereby.

Removably mounted on the heater or stove 10 is 40 a hover or hood consisting of sheet metal sections, preferably four in number, and indicated at 33, 34, 35 and 36. The side hood sections 33 and 34 are provided with bolting flanges 37 and 37' at their upper edges which at an intermediate point 45 are oppositely recessed to fit around the stack or chimney 14. The rear section 35 is detachably connected at its opposite side edges by bolts 38 to the adjacent edges of the sections 33 and 34; while the front section 36 is hinged as at 39 to a gusset plate 40 which spans the converging upper front edges of the side sections 33 and 34 and is connected to said latter edges. Thus, the front section may be conveniently raised as in Fig. 2 to gain access to the door 15 of the stove or the control unit mounted on the door.

The side sections 33 and 34 rest on brackets 42 and 43 which in turn rest on the top wall of the stove, to thereby give proper clearance for the hood or hover with respect to the stove.

In operation, whenever it is desired to charge the stove with fuel, the hood section 36 may be swung upwardly and the stove charged through the door 15. The adjusting screw 28 may be set so that the thermostatic disc or discs 30 will expand and contract within a predetermined temperature range and regulate the damper 20. When the thermostatic discs 30 expand, the weighted end of the lever 23 is raised and the opposite end lowered, thereby permitting the damper 20 to move towards closed position and retarding combustion of the fuel. When the said discs contract, the weighted end of the lever 23 is lowered and the damper 20 moved towards open position, thereby increasing the draft in the stove and accelerating combustion of the fuel. The shield 18' on the inner side of the door 15 causes a down draft into and over the fuel in the stove.

The thermostatic unit may be assembled in its entirety with respect to the supporting arm 21 and the latter then hung onto the door 15 and the link 25 connected to the hook 26. The thermostatic discs 30 are removable and replaceable at any time desired. In certain instances, a purchaser may desire to buy the brooder and stove without the automatic control, in which event the damper 20 may be manually controlled. If at any time repairs are to be made to the control assembly or unit, the arm 21 may be easily and quickly removed, carrying the entire unit therewith. The parts may be manufactured and sold at a relatively low cost, while at the same time the advantages of automatic regulation are optionally available.

The feet of the brackets 42 and 43 extend at a substantially true radius from the peripheral wall of the stove and constitute the sole means of support for the hood or hover, note Fig. 5, thereby reducing heat transfer to a minimum while at the same time providing maximum supporting strength.

It will be obvious to those skilled in the art that certain limited changes in construction and design of the improved brooder may be adopted without departing from the spirit or scope of the invention as defined by the appended claims.

What is claimed is:

1. In a brooder, a stove having a substantially cylindrical body portion defining a drum, the

front end of said drum having a door hingedly mounted thereon, an arm having a detachable connection with said door and extending outwardly therefrom, a movable damper mounted on said door, a lever pivotally suspended from said arm, one end of said lever being weighted and the opposite end of said lever being connected to said damper, an adjusting screw threaded through the end of said arm and having a supporting member on the upper end thereof, and a thermostatic disc removably disposed on said supporting member and contacting the weighted end of said lever and whereby expansion and contraction of said disc will effect rocking of the lever and regulate the opening and closing movements of said damper.

2. In a brooder, a wood burning stove having a substantially cylindrical body defining a drum, a door for the stove hingedly mounted in the one end wall of the drum, said door being formed with a draft opening having an outwardly projected wall therearound, a shield on the inner side of said door open at its lower end to cause a down draft of air passing through said opening, a damper hingedly connected to the wall around said opening, an arm detachably connected to the door above said damper, a sheet metal guide member overlying said arm and projecting downwardly therefrom, a lever extending through said guide member and pivoted to the latter, the inner end of said lever being connected to said damper, a weight mounted on the outer end of said lever, a screw threaded through the inwardly projecting extremity of said arm and having a disc supporting member on the upper end thereof, and a thermostatic disc disposed on said supporting member and contacting the weighted end of said lever and adapted to control the damper through expansion and contraction due to temperature changes within the region of the stove.

3. In a brooder, a stove having a draft opening, a damper for controlling the draft through said opening, an arm detachably connected to the stove and projecting downwardly and outwardly over said damper, a lever pivotally suspended from said arm, the inner end of said lever being connected to said damper and the outer end of said lever being provided with a weight, a thermostatic disc interposed between the outer end of said arm and the weighted end of said lever, and means for adjusting said disc with respect to said lever.
